UNITED STATES PATENT OFFICE

MELBOURNE L. CARPENTIER, OF HIGHLAND PARK, MICHIGAN, ASSIGNOR TO CHRYSLER CORPORATION, OF DETROIT, MICHIGAN, A CORPORATION OF DELAWARE

PROPELLER DRIVING UNIT

Application filed September 22, 1930. Serial No. 483,568.

This invention relates to improved driving mechanism for motor boat propellers.

The main objects of the invention are to provide mechanism of this kind which includes separable sections that are adapted to be conveniently assembled in the hull of a boat, one from each respectively opposite side of the bottom of the hull; to provide a propeller driving unit which requires the formation of only a substantially small passage in the bottom of the hull for its accommodation so as to obviate the packing heretofore required in order to form a water tight seal; to provide an extensible unit of this kind which is adapted to be used in conjunction with motors or driving members having various elevational locations with respect to the bottom of the hull of a boat; to provide an angularly adjustable driving unit; to provide a propeller driving unit of this kind which may be readily conditioned to drive the propeller in either direction; to provide driving mechanism in which the same parts may be used to selectively drive a propeller in both directions, so as to permit units of identical construction to be conditioned, during assembling, for use on either the starboard side or the port side of a twin screw propelled boat; and to provide a driving mechanism for operatively connecting a propeller to a motor which does not require the use of universal joints, or other flexible connections, and thus to obviate the vibrations generally present in devices which require such flexible connecting elements.

An illustrative embodiment of my invention is shown in the accompanying drawings, in which:

Fig. 1 is a vertical section of a propeller driving unit embodying my invention.

Fig. 2 is a rear side elevation of the unit shown in Fig. 1.

Fig. 3 is a side elevation of a motor boat showing my improved propeller driving mechanism.

Fig. 4 is a rear end elevation illustrating an application of the propeller driving mechanism in a twin screw driven boat.

Fig. 5 is a vertical section taken on the line 5—5 of Fig. 1.

Fig. 6 is an enlarged fragmentary section showing the propeller shaft supporting and driving mechanism in detail.

In the form shown, the propeller driving unit includes an externally located propeller shaft having a propeller on one end. The propeller shaft is journaled in bearings which are supported in a housing having a tubular extension which is adapted to be inserted through an opening in the bottom of the hull of a boat and secured thereto so as to be supported independently by the bottom of the hull. The tubular extension forms one section of a separable shaft housing which has an extensible concentric sleeve arranged in telescoping relation in the upper open end thereof. Mounted on the sleeve is a gear housing which is pivotally supported on a transmission case of a driving member so as to be angularly adjustable. A substantially vertical shaft including separable and extensible sections having beveled gears on its respectively opposite ends provides a connecting member for transmitting power from the driving shaft of a driving member to the propeller shaft. A reversible bevel gear mounted on the propeller shaft in mesh with the adjacent bevel gear of the extensible shaft is adapted to be placed on either side of the latter bevel gear during assembling so as to drive the propeller shaft and the propeller in either a clockwise or counter-clockwise direction.

In the illustration shown, a motor boat 1 is provided with an internal combustion engine 2 or other prime mover having a transmission 3 from which a driving shaft 4 extends. The rear end of the driving shaft 4 is journaled in a bearing 5 mounted in a tubular boss 6 formed on the rear wall of a transmission casing 7. The shaft 4 has a beveled gear 8 on its outer end which is enclosed within a casing 9 having an inclined open side that is provided with a removable cover 10. The front wall 11 of the casing 9 has an aperture for receiving the shaft 4 and it is provided on its forward side with a circular flange 12 which is received in the rear end of the tubular boss 6. The casing 9 is rotatably adjustable with respect to the

transmission casing 7 and it may be securely held in a selected position by bolts 13 which extend through arcuate slots 14 in the rear wall 11 of the casing and are threaded in the end of the tubular boss 6.

5 The casing 9 has an open lower end through which a sleeve 15 having a radial flange 16 extends. The radial flange 16 is seated upon the lower extremity of the casing and rigidly attached thereto by bolts 17 which extend through the flange and are threaded in the walls of the casing. The sleeve 16 also has an enlarged upper extremity in which a bearing 18 is mounted.

15 The lower end of the sleeve 15 is received in telescoping fashion in the upper end portion of a tubular housing 19 which extends upwardly through an opening 20 in the bottom 21 of the hull of the boat 1. This housing is provided with a radial flange 22 located adjacent the outer surface of the bottom 21 of the hull and secured thereto by bolts 23. The flange 22 forms a water tight seal around the housing 19 preventing water 20 from leaking through the opening 20. A cap 24 having a central aperture for receiving the sleeve 15 is threaded on the upper extremity of the tubular housing 19. Located between the end of the cap and the extremity 25 of the housing 19 is a packing ring 25 by which the outer surface of the sleeve 15 is frictionally engaged so as to prevent the leakage of water into the housing 19 and of oil therefrom.

30 Formed on the lower end of the tubular housing 19 is a propeller shaft supporting head 26 having a substantially bullet-shaped contour in which spaced bearings 27 and 28 are mounted. The head 26 has open front 35 and rear extremities which are provided with threaded closures 29 and 30 through which the bearings 27 and 28, respectively are insertable. A propeller shaft 31 journaled in the bearings 27 and 28 and having a propeller 40 32 extends rearwardly through an aperture in the threaded cap 30. The threaded cap 30 has a packing gland 33 by which a seal is formed between the periphery of the propeller shaft 31 and the cap 30 so as to prevent the leakage of water into the interior of the head 26. The shaft 31 is externally located with respect to the hull of the boat and is misaligned with respect to the driving shaft 4.

45 The driving shaft 4 and the propeller shaft 55 1 are connected together by an extensible shaft which includes separable shaft sections 34 and 35. These shaft sections are splined together in telescoping relation, as shown at 36 in Fig. 1, and they are provided on their 60 respectively opposite ends with bevel gears 37 and 38 which mesh with the bevel gear 8 of the driven shaft 4 and with a bevel gear 39 on the propeller shaft 31, respectively. The meshed bevel gears 8 and 37 are located in the 65 gear casing 9 and the meshed gears 38 and 39

are located in the head 26 of the propeller shaft. This extensible shaft, together with the extensible housing within which it is mounted, permit the propeller driving unit to be conditioned for use in connection with driving members which are located at various elevations with respect to the bottom of the hull of a boat.

70 The sleeve 15 of the housing and the upper section 35 of the shaft are independently supported on the transmission casing 7, and driving shaft 4, and the tubular extension 19 of the shaft housing and the lower section 35 of the extensible shaft are independently supported on the bottom 21 of the hull. With this construction, the unit may be conveniently assembled in a boat by first attaching the upper portion of the propeller driving mechanism which includes the shaft housing sleeve 15 and upper section 35 of the extensible shaft, to the transmission casing 7. This part of the mechanism may be adjustably positioned angularly with respect to the bottom of the hull so as to condition it for use in connection with hulls of various shapes. The next operation involved in assembling the propeller driving mechanism in a boat consists in inserting the tubular part 19 of the lower portion of the mechanism, together with the lower section 34 of the shaft, upwardly through the aperture 20 in the bottom 21 of the hull until the radial flange 22 is seated upon the lower surface of the bottom of the hull. In this manner the driving unit may be conveniently installed from the respectively opposite sides of the bottom of the hull without requiring the mechanism to be materially disassembled.

75 80 85 90 95 100 105 110 115 120 125 130 The bevel gear 39 of the propeller shaft 31 is keyed at 40 to the shaft and is held in spaced relation to the rear end of the head 26 by a sleeve 41 which has a radial flange 42 engaging the front side of the bearing 28 in which the propeller shaft is journaled. The bearing 28 is held against rearward movement by a collar 43 which is integrally formed on the shaft 41. The bevel gear 38 carries a hub 44 of reduced diameter on which the bearing 27 is seated. A shoulder 45 is also formed on the bevel gear 39 for engaging the rear side of the bearing 27 which is held against frontward movement by a washer 46 on the extreme front end of the propeller shaft 31.

Assuming that the driving shaft 4 rotates in a clockwise direction, as shown by the arrow in Fig. 1, it will be seen that the extensible shaft and the propeller shaft are rotated in a counter-clockwise direction for the reason that the bevel gears 8 and 39 are each located 120 on the same side of the extensible shaft. With my improved propeller driving mechanism, the direction of rotation of the propeller may be predetermined during assembling of the unit by selectively placing the bevel gear 39 125 130

on either the front or rear sides of the bevel gear 38, as viewed in Fig. 1. The construction of the mechanism permits this selection without necessitating the use of parts of different designs. To reverse the direction of rotation, of the propeller, it is merely necessary to remove the propeller shaft from the head 26 by first removing the nut 47 after the cap 29 is removed. The shaft 31 may then be moved rearwardly after the cap 30 of the shaft housing is displaced and the bevel gear 39 and sleeve 41 may be lowered from the head 26 through an opening in the bottom thereof which is normally closed by a cover 48. In reassembling the mechanism, the bevel gear 39 is placed in the dotted line position shown at 49 in Fig. 6 and the sleeve 41 is reversed end for end with respect to the position shown in Fig. 1. This feature of the invention permits propeller driving units of identical construction to be used on the port side and starboard sides, respectively of twin screw propelled boats of the type shown in Fig. 4, it being understood that the pitch of one of these propellers is reversed with respect to each other.

With the above propeller driving mechanism, a positive driving connection is formed between the propeller and the driving member without the aid of universal joints, or other flexible connections which have heretofore been the source of vibration in power transmissions of motor boats. The elimination of these flexible joints materially reduces vibration and prolongs the life of the bearings and other parts of the structure.

Although but one specific embodiment of this invention has herein been shown and described, it will be understood that various changes in the size, shape and arrangement of parts may be made without departing from the spirit of my invention and it is not my intention to limit its scope other than by the terms of the appended claims.

45 What I claim is:

1. In a motor boat, a driving member therein, a support for said driving member within the hull of said boat, a propeller driving mechanism including a pair of telescoping separable sections, one swingably mounted on said support, the other section being rigidly secured to said hull, and releasable means for rigidly fixing said swingable section to said support.

55 2. In a motor boat, a driving member therein, a support within the hull of said boat and a propeller driving mechanism including a pair of telescoping separable sections, one swingably mounted on said support, the other section being rigidly secured to said hull, said propeller driving mechanism being extensible so as to condition the same for use in conjunction with driving members having various elevational locations with respect to the bottom

60 3. In a motor boat, a driving member therein, a support within the hull of said boat, and a propeller driving mechanism including a pair of separable sections, one of said sections being insertable from the exterior through an opening in the bottom of said hull and adapted to be secured thereto; the other section being adjustably mounted on said support, and means for securing the latter section in a selected position, said propeller driving mechanism being extensible so as to condition the same for use in conjunction with driving members having various elevational locations with respect to the bottom of said hull.

65 4. In a motor boat, a driving member therein, a shaft housing extending from the proximity of said driving member through an opening in the bottom of the hull of said boat, an enlarged head on the external end of said housing, a connecting shaft in said housing, meshed gears on the adjacent portions of said driving shaft and connecting shaft, a gear on said connecting shaft, a propeller shaft journaled in said head extending on diametrical 70 75 80 85 90 95 100 105 110 115 120 125 130

opposite sides of the latter gear and having unobstructed sections on opposite sides thereof for receiving a pinion, and a pinion adapted to be selectively mounted on diametrically opposite sides of the adjacent gear of said connecting shaft so as to predetermine the direction of rotation of said propeller shaft.

5. In a boat having a motor, a propeller driving unit including an internal driving shaft, a support therefor, a misaligned driven shaft, a support for said driven shaft, a connecting shaft including separable sections, coaxing members on the adjacent portions of said shafts for transmitting power from said driving shaft to said driven shaft, and a housing for said connecting shaft including a pair of separable housing sections, one fixed to the hull of said boat and the other swingably mounted on said motor.

6. In a boat having a motor including a driving shaft, a propeller driving mechanism including a pair of separable sections, one swingably mounted on said motor having an axis concentric with said driving shaft and the other supported by the hull of said boat, and releasable means for rigidly fixing said swingable section to said motor.

MELBOURNE L. CARPENTIER.
